UNITED STATES PATENT OFFICE.

FELIPE GIROUD, DECEASED, LATE OF NEW YORK, N. Y., BY EDITH ELMIRA CHAPMAN,
EXECUTRIX, OF NEW YORK, N. Y., ASSIGNOR TO PACKAGE MACHINERY COMPANY,
A CORPORATION OF MASSACHUSETTS.

WRAPPING-MACHINE.

1,117,130.

Specification of Letters Patent. Patented Nov. 10, 1914.

Application filed March 5, 1914. Serial No. 822,639.

To all whom it may concern:

Be it known that FELIPE GIROUD, late a citizen of the island of Cuba, and a resident of the city of New York, in the county 5 of New York and State of New York, deceased, did invent a certain new and useful Improvement in Wrapping-Machines, of which the following is a specification.

This invention relates to improvements 10 on machines in which an article and a wrapper are successively passed through folding devices, whereby the wrapper is folded upon the article.

The object of the invention is to provide 15 means whereby a wrapper can be folded around an article in such a manner that all of the folds are so placed that a second wrapper in the form of a single band folded around the wrapped article will cover all 20 of the folds of the first wrapper.

The invention consists of two wrapper folding channels in alinement, each channel having stationary folders, the folders of one channel being in alinement with a folder 25 of the other channel. A wrapper feeding mechanism is provided which is adapted to move a wrapper to rest between said wrapper folding channels, and into range with a paste applying device. A reciprocating 30 plunger is arranged to move a partially wrapped article through one of said wrapper folding channels, whereby the wrapper is folded upon the article, and as the plunger continues its forward movement, the wrapped 35 article forces the second wrapper through the second wrapper folding channel, whereby the second wrapper is partially folded upon the folds of the first wrapper. Two swinging folders complete 40 the folding of the second wrapper upon the folds of the first wrapper.

In the accompanying drawings: Figure 1 is a sectional plan view of part of a machine embodying the invention. Fig. 2 is 45 a sectional elevation of the line II-II of Fig. 1. Fig. 3 is a view similar to Fig. 1, showing certain parts in a different position. Figs. 4 to 10 inclusive represent the different stages which a wrapper passes through in being folded upon an article, during partial travel of said article and 50 wrapper through the machine. Figs. 11,

12 and 13 represent the different stages which a second wrapper passes through in being folded upon the wrapped articles, and 55 second wrapper through part of the machine. Fig. 14 is a sectional elevation on the line XIV-XIV of Fig. 3. Fig. 15 is a transverse section on the line XV-XV of Fig. 3. Fig. 16 is a section on the line XVI-XVI of Fig. 3, showing means for applying paste to the second wrapper.

A power driven shaft 1 is journaled at 2 in the main frame 3. A lever 4 is pivoted at 5 and provided with a roller 6 which 60 engages a cam 7 secured to shaft 1. Lever 4 is connected by a link 8 to a slide 9 which rides in guides 10. Forming part of slide 9 is a plunger 11. Lever 4 is also connected by a link 12 to a lever 13 which is pivoted 65 at 14 to the main frame. The lever 13 is connected by a link 15 to a slide 16 which rides in guides 17. Forming part of slide 16 is a plunger 18 which moves transversely to the line of travel of plunger 11. Cam 75 7 causes back and forth movements of arm 4, which movements are transmitted to arm 13 by means of link 12.

By reference to Figs. 1, 3, 14 and 15, it will be seen that the plungers which are 80 connected to the arms 4 and 13 have such relation to each other that when one plunger reaches the end of a forward movement, the other plunger will have reached the end of a backward movement; and vice 85 versa. A bevel gear wheel 19 secured to shaft 1 is in mesh with a bevel gear wheel 20 which is secured to a vertical shaft 21. Vertical shaft 21 rotates in a bearing 22 and extends upward for the purpose of actuating a paper feed mechanism. The paper feed mechanism is omitted as it forms no 90 part of the present invention. A wrapper 23 is fed by said paper feed mechanism to a guide 24 which has supports 25 upon 95 which the wrapper rests. To the rear of guide 24 is a support 26 upon which an article 27 is placed after the plunger 11 has reached the end of its backward movement. Then as plunger 11 moves forward 100 it will force the article 27 against the wrapper 24, thereby forcing the wrapper between an upper plate 28 and a lower plate 29, and between central side folders 30 of

a channel 31, causing the wrapper to be folded upon the article in the manner shown in Fig. 4. Continued forward movement of plunger 11 causes upper side flaps *a* of the wrapper to take against upper folders 32, causing said flaps to be folded to the position shown in Fig. 5. Further forward movement of plunger 11 causes lower side flaps *b* to take against lower folders 33, 10 causing said flaps to be folded to the position shown in Fig. 6. At the end of forward movement of plunger 11, said article and wrapper will be moved into range with the plunger 18 which is then at the end of its 15 backward movement. A side end flap *c* will then be in range with slide 34 which has movement on guide 35 placed transversely to the line of plunger 11. Pivoted at 36 to the slide 34 is a pawl 37 which extends into range with a projection 38 on plunger 18. By means of a spring 39, an inclined face 40 of the pawl 37 is held against a pin 41. During backward movement of plunger 18, pawl 37 is moved aside by projection 38, 20 said pin 41 permitting the pawl to be moved into range with said projection 38, at the end of the backward movement of said plunger.

The mechanism so far described is shown 30 and described in an application for patent filed by Felipe Giroud, July 14, 1911, Serial No. 638,484, for an improvement in wrapping machines, and is inserted in this application in order that coöperation there- 35 with of other mechanism, hereinafter described, can be understood.

Secured to vertical shaft 21 is a chain wheel 42, over which rides an endless chain 43. The chain 43 traveling in the direction 40 indicated by the arrow in Fig. 3, passes over an idle chain wheel 44, and over a chain wheel 45, thereby causing rotation of chain wheel 45 in the direction indicated by an arrow. From chain wheel 45 the chain 43 45 passes over and causes revolution of a chain wheel 46 in a direction opposite to that of chain wheel 45. From chain wheel 46 the chain 43 passes over and causes revolution of a chain wheel 47 in the direction indicated by an arrow. From chain wheel 47 the chain 43 passes over an idle chain wheel 48, and in returning to chain wheel 42, passes over an idle chain wheel 49. The chain wheel 47 is secured to a vertical shaft 50 which rotates in a bearing 51. To the upper end of shaft 50 is secured a rubber finger 52, which during rotation of said shaft takes against and causes one of a series of wrappers 53 to be moved into engagement 55 between feed rollers 54 and 55. Also secured to vertical shaft 50 is a cam 56, which during rotation of the shaft, takes against a pin 57 forming part of a slide 58, thereby causing movement of said slide, 60 which movement is opposed by a spring 59;

resulting in reciprocating movements of the slide. Said reciprocating movements of the slide cause rotation of a knife 60, which knife serves the purpose of preventing movement of more than one of the wrappers 53 by means of the rubber finger 52 on vertical shaft 50.

The means whereby movement of slide 58 causes revolution of knife 60 is not described, as it forms no part of the present 75 invention.

The feed roller 54 is secured to a vertical shaft 61 to which the chain wheel 46 is also secured. Secured to vertical shaft 61, is a gear wheel 62 which is in mesh with a gear wheel 63 secured to a shaft 64, having the feed roller 55 secured thereto. It will be readily seen that rotation of chain wheel 46 by means of chain 43 causes rotation of the feed rollers 54 and 55.

Rotation of the feed rollers causes the wrapper fed between them to be moved forward to rest across the line of travel of the plungers 18, a portion of said wrapper being in range with the folders of one channel 90 which are in alinement with a folder of the other channel. The finger 52 is so placed on vertical shaft 50 that said finger will cause movement of a wrapper 53 into engagement between said feed rollers, after the mechanism actuating plungers 11 and 18 has caused return movement of plunger 18.

The chain wheel 45 is secured to a vertical shaft 65 which rotates in a bearing 66. To the upper end of shaft 65 is secured a roller 67 which rotates in a receptacle 68 in which paste 69 is placed, the receptacle having an opening 70 through which the roller carries paste to the exterior of the receptacle. Also secured to vertical shaft 65 105 is a gear wheel 71 which is in mesh with a gear wheel 72 secured to a vertical shaft 73, having a finger 74 secured thereto. Rotation of vertical shaft 65 causes rotation of the shaft 73 carrying the finger 74, and the finger is adapted, during said rotation, to take paste from the roller 67 and to deposit said paste upon a portion of the wrapper 53, in the manner shown at *g* in Fig. 10.

When plunger 11 moves backward, plunger 18 moves forward, and the projection 38 on said plunger takes against pawl 37; resulting in forward movement of the pawl and slide 34. The slide 34 taking against side end flap *c*, causes said flap to be folded from the position shown in Fig. 6 to the position shown in Fig. 7. During said forward movement of the pawl 37, the inclined face 40 thereof riding on pin 41, will cause the pawl to be moved out of engagement with projection 38; and the pawl and slide will then be returned to their original position by means of the spring 39.

As plunger 18 continues its forward movement, it will take against and accordingly 130

force the article and wrapper forward along a channel 75 causing the side end flap *d* to take against a central end folder 76, which will cause said side end flap to be folded from the position shown in Fig. 7 to the position shown in Fig. 8. Continued forward movement of plunger 18 and consequent forward movement of the article and wrapper along channel 75 causes upper end flap *e* to take against an upper folder 77, which will cause said upper end flap to be folded from the position shown in Fig. 8 to the position shown in Fig. 9. Further forward movement of the article and wrapper by means of plunger 18 causes the lower end flap *f* to take against a lower folder 78, which folds said lower end flap from the position shown in Fig. 9 to the position shown by dotted lines in Fig. 10. During further forward movement of plunger 18, the wrapped article being thereby moved against the second wrapper 53, and together with the second wrapper forced between two side folders 79, causes the second wrapper to be folded from the position shown in Fig. 10 to the position shown in Fig. 11. At the end of forward movement of plunger 18, the wrapped article, and the second wrapper folded as in Fig. 11, will be moved into a receiving channel 80. An end flap *h* of the second wrapper will then be in range with a swinging folder 81, and an end flap *i* will be in range with a swinging folder 82. The folder 81 is pivoted at 83 and is provided with a downward extension 84, having a roller 85 at its lower end adapted for engagement with a cam 86 secured to the driving shaft 1. The roller 85 is held in engagement with cam 86 by means of a spring 87. The folder 82 is pivoted at 88 and is provided with a downward extension 89, having a roller 90 at its lower end, held in engagement with a cam 91, on the driving shaft, by means of a spring 92. The cams 86 and 91 have such relation to each other and to the mechanism actuating plungers 11 and 18, that after said mechanism causes return movement of plunger 18, cam 86 will cause folder 81 to turn the flap *h* from the position shown in Fig. 11 to the position shown in Fig. 12, and after return movement of folder 81, cam 91 will cause folder 82 to turn flap *i* from the position shown in Fig. 12 to the position shown in Fig. 13. The edge *g* on flap *i* will cause said flap to adhere to flap *h*, thereby holding the second wrapper folded in the manner shown.

By reference to the Figs. 4 to 13 inclusive, it will be seen that all folds of the first wrapper are covered by the second wrapper when folded as shown in Fig. 13.

Having described the invention, what is claimed is:

1. A wrapping machine comprising two

wrapper folding channels in alinement, each one of said wrapper folding channels being provided with stationary folders; means whereby a wrapper is moved to rest between said two wrapper folding channels; means whereby paste is applied to part of said wrapper; a reciprocating plunger; means whereby a partially wrapped article is moved to rest between one of said wrapper folding channels and said plunger; means for actuating said plunger whereby forward movement thereof causes said partially wrapped article to be forced through said wrapper folding channel, thereby causing the wrapper of said partially wrapped article to be folded upon the article; further forward movement of said plunger causing said wrapped article and the first named wrapper to be forced through the second wrapper folding channel, whereby the first named wrapper is partially folded upon the wrapped article; and two swinging folders adapted to finally fold the first named wrapper upon the wrapped article, said applied paste serving to hold the first named wrapper folded, substantially as described.

2. A wrapping machine comprising two wrapper folding channels in alinement each one of said wrapper folding channels being provided with stationary folders, the folders of one channel being in alinement with a folder of the other channel, means whereby a wrapper is moved to rest between said two wrapper folding channels, a portion of said wrapper being in range with said folders of one channel which are in alinement with a folder of the other channel; a reciprocating plunger; means whereby a partially wrapped article is moved to rest between one of said wrapper folding channels and said plunger; means for actuating said plunger whereby forward movement thereof causes said partially wrapped article to be forced through said wrapper folding channel, thereby causing the wrapper of said partially wrapped article to be folded upon the article; further forward movement of said plunger causing said wrapped article and the first named wrapper to be forced through the second wrapper folding channel, whereby the first named wrapper is folded upon the wrapped article.

3. A wrapping machine comprising two wrapper folding channels in alinement, each one of said wrapper folding channels being provided with stationary folders; means whereby a wrapper is moved to rest between said two wrapper folding channels; means whereby paste is applied to part of said wrapper; a reciprocating plunger; means whereby a partially wrapped article is moved to rest between one of said wrapper folding channels and said plunger; a wrapper folding mechanism; means for actuating said plunger whereby a partial for-

ward movement thereof causes said wrapper folding mechanism to be actuated whereby a side flap of the partially folded wrapper is folded upon the article; further forward movement of said plunger causing said partially wrapped article to be forced through said wrapper folding channel, thereby causing the wrapper of said partially wrapped article to be folded upon the article; further forward movement of said plunger causing said wrapped article and the first named wrapper to be forced through the second wrapper folding channel, whereby the first named wrapper is partially folded upon the wrapped article; and two swinging folders adapted to finally fold the first named wrapper upon the wrapped article, said applied paste serving to hold the first named wrapper folded, substantially as described.

4. A wrapping machine comprising two wrapper folding channels in alinement, each one of said wrapper folding channels being provided with side stationary folders, means whereby a wrapper is moved to rest between said two wrapper folding channels; portions of said wrapper being in range with said side stationary folders, means whereby paste is applied to one of said portions of the wrapper; a reciprocating plunger, means whereby an article having an inner wrapper partially folded thereon is moved to rest between one of said wrapper folding channels and said plunger, the unfolded portions of the inner wrapper being in range with said side stationary folder; means for actuating said plunger whereby forward movement thereof causes said article and wrapper to be forced through said wrapper folding channel, thereby causing said unfolded portions of the inner wrapper to be folded against a side of the article, further forward movement of said plunger causing the wrapped article and the first named wrapper to be forced through the second wrapper folding channel, whereby the first named wrapper is partially folded upon the wrapped article; and folding devices adapted to finally fold the first named wrapper upon the wrapped article, said applied paste serving to hold the first named wrapper folded, substantially as described.

5. A wrapping machine comprising two wrapper folding channels, in alinement, each one of said wrapper folding channels being provided with side stationary folders, means whereby a wrapper is moved to rest between said two wrapper folding channels; portions of said wrapper being in range with said side stationary folders; a reciprocating plunger; means whereby an article having an inner wrapper partially folded thereon is moved to rest between one of said wrapper folding channels and said plunger, the un-

folded portions of said inner wrapper being in range with said side stationary folders; means for actuating said plunger whereby forward movement thereof causes said article and wrapper to be forced through said wrapper folding channel, thereby causing said unfolded portions of the inner wrapper to be folded against a side of the article; further forward movement of said plunger causing the wrapped article and the first named wrapper to be forced through the second wrapper folding channel, whereby the first named wrapper is partially folded against a side, and against said part of the inner wrapper folded against a side of the wrapped article; and two swinging folders adapted to finally fold the first named wrapper upon the wrapped article.

6. A wrapping machine comprising two wrapper folding channels in alinement, each one of said wrapper folding channels being provided with stationary folders; a paste applying device; a wrapper feeding mechanism adapted to move a wrapper to rest between said two wrapper folding channels, and into range with said paste applying device, whereby paste is applied to part of said wrapper; a reciprocating plunger; means whereby a partially wrapped article is moved to rest between one of said wrapper folding channels and said plunger; means for actuating said plunger whereby forward movement thereof causes said partially wrapped article to be forced through said wrapper folding channel, thereby causing the wrapper of said partially wrapped article to be folded upon the article, further forward movement of said plunger causing said wrapped article and the first named wrapper to be forced through the second wrapper folding channel, whereby the first named wrapper is partially folded upon the wrapped article; and folding devices adapted to finally fold the first named wrapper upon the wrapped article, said applied paste serving to hold the first named wrapper folded, substantially as described.

7. A wrapping machine comprising two wrapper folding channels in alinement, each one of said wrapper folding channels being provided with stationary folders, the folders on one channel being in alinement with a folder of the other channel; a wrapper feeding mechanism adapted to move a wrapper to rest between said two wrapper folding channels, a reciprocating plunger; means whereby a partially wrapped article is moved to rest between one of said wrapper folding channels and said plunger; means for actuating said plunger whereby forward movement thereof causes said partially wrapped article to be forced through said wrapper folding channel, thereby causing the wrapper of said partially wrapped article to be folded upon the article, further

forward movement of said plunger causing said wrapped article and the first named wrapper to be forced through the second wrapper folding channel, whereby the first named wrapper is partially folded upon the wrapped article; and two swinging folders adapted to finally fold the first named wrapper upon the wrapped article.

Signed at New York city, in the county
